UNITED STATES PATENT OFFICE.

EDWARD CHESHIRE, OF CINCINNATI, OHIO, ASSIGNOR OF ONE-HALF TO
ELIZABETH CHESHIRE, OF SAME PLACE.

BOOK-SEWING MACHINE.

SPECIFICATION forming part of Letters Patent No. 317,506, dated May 12, 1885.

Application filed May 28, 1884. (No model.)

To all whom it may concern:

Be it known that I, EDWARD CHESHIRE, a citizen of the United States, residing at Cincinnati, in the county of Hamilton and State of Ohio, have invented certain new and useful Improvements in Book-Sewing Machines, of which the following is a specification.

My invention relates to a book-sewing machine, more particularly to detail improvements in the machine forming the subject-matter of an application for Letters Patent of the United States, filed by Elizabeth Cheshire and myself, jointly, May 24, 1883, serial number 96,063, all of which will be fully herein-
15 after described.

In the accompanying drawings, Figure 1 is a plan view of the upper working parts of a book-sewing machine embracing my improvements. Fig. 2 is a plan view of the automatic tension devices. Fig. 3 is a transverse section taken on line $x-x$, Fig. 2, showing one of the tension-springs and a take-up spring, together with the plate and shaft upon which they are mounted. Fig. 4 is a transverse section taken on line $y-y$, Fig. 2, showing another spring-tension plate and its depressing eccentric. Fig. 5 is a perspective view showing a portion of the needle and main frames and the device for operating the spring tension and take-up devices illustrated in Figs. 2, 3, and 4. Fig. 6 is an elevation of one of the eye-plates through which the sewing-twines are passed and guided from the balls to the tension and take-up springs. Fig. 7 is a perspective view of the slotted transverse bar upon which the presser and push-up springs are adjustably mounted in position over the meeting point of the feed and needle frames for operation upon the signature in process of sewing. Fig. 8 is a cross-section of the slotted bar, taken on line $x'-x'$, Fig. 7, showing one of the presser-springs attached thereto, and an elevation of a broken-off portion of one of the teeth of the comb shape plate. Fig. 9 is a broken-off plan of the fore end of the needle-frames, showing the "kettle-stitch" take-up thereon. Fig. 10 is a front elevation of the same. Fig. 11 is an inside sectional elevation of one of the kettle-stitch needle-frames, taken on line $z-z$, Fig. 9. Fig. 12 is a front elevation of the feed-carriage, showing one of

the pendent arms broken off. Fig. 13 is a cross-section of the forward end of the feed-carriage, showing the toothed signature-supporting plate, one of the outer bumpers, and the transverse rod or bar beneath the edge of said toothed plate for supporting the shuttle-thread. Fig. 14 is a cross-section similar to Fig. 13, showing the feed-carriage with its toothed signature-plate, transverse shuttle-thread-supporting rod, and one of the pendent arms for compactly pressing the sewed signatures and keeping the hanging leaf or leaves of the signature on the feed table perpendicular, which pendent arms are fully shown and described in said application, filed May 24, 1883, and which we deem unnecessary to describe herein, as they are not claimed. Fig. 15 is a perspective view of one of the end bumpers or presser-heads of the feed-carriage, showing a bow-spring at its top for guiding the shuttle-thread through the slit in the signature to the kettle-stitch twine. Fig. 16 is a plan view of a portion of the feed-carriage and main frame, showing the toothed signature-plate with a slitting-knife and guide mounted thereon, and the shuttle-race frame with a shuttle-catch and temporary locking device attached thereto, and holding the shuttle firmly in place in connection with the picker-staff driving-head. Fig. 17 is a perspective view of one of the adjustable signature-guides. Fig. 18 is a perspective view of the adjustable knife and guide-supporting plate. Fig. 19 is a broken inside elevation showing a part of the main frame, one of the slide guides of the feed-table, the shuttle-raceway, the temporary lock-bar for the feed-carriage, and the cam on the driving-shaft for raising said lock-bar into locking engagement with the feed-table. Fig. 20 is a transverse section of the device shown in Fig. 19, taken on line $y-y$, but showing a broken section of the feed-table locked in position for the sewing operation. Fig. 21 is a bottom plan view of the outer fore corner of either of the kettle-stitch frames, showing the adjustable bent plate thereon for operating the shuttle-locking device.

A represents the main frame of the machine, which, in general, together with suitable driving mechanism, (not shown,) is identi-
100

cal with that shown and described in the application aforesaid. The same or any other suitable power mechanism may be employed to drive the feed and sewing devices, and as 5 I do not claim any special means herein the illustration of them in the accompanying drawings or any description will be unnecessary.

B represents the feed-carriage, having a 10 transverse series of teeth B' along the inner edge of its table B'' and a tongue, b, on both its side edges, which travel in grooves a in the upper part of the main frame.

C represents a vertical bar sliding in a clip, 15 C', attached to the main frame. The lower end of bar C preferably engages the periphery of a cam, c, keyed to the driving-shaft c', (shown in section in Fig. 19,) and is provided at its upper end with a wedge shape tongue, c'', which 20 enters a notch, b', cut in the opposite edges or tongues b of the feed-table. This vertical bar effectually locks the feed-carriage in place during the sewing operation, and thereby prevents any forward or rearward movement 25 thereof at the time the shuttle is driven across, thus obviating any dislocation of the signature out of proper relation with the shuttle and the sewing-needles. The bar C drops by gravity after the sewing operation, 30 on the rotation of the cam, and permits the return movement of the feed-carriage for the release of one signature and the feeding of another.

D represents a bar provided at one end 35 with a knife edge, d, and at the other with an upright arm, d'. Bar D is pivoted intermediate its ends to a plate, D', which is adjustably secured to the forward edge of the feed-table over the teeth B' in a position to 40 bring the knife d adjacent the fold of the signature whose end lies upon it.

E represents a spring secured at one end to plate D', and bearing at its other end against the knife-bar to return it to its normal position after its cutting operation, which will be 45 presently described.

e is a rib on the bottom of plate D', fitting 50 into a groove, e', in the face of the feed-table, to prevent any lateral or torsional movement of the plate during the operation of the knife-bar, and to accurately and firmly set the plate in place.

F represents a guide, adjustably secured 55 upon plate D' in rear of the knife-bar.

The knife bar D, plate D', and guide F are arranged in duplicate at either end the toothed plate of the feed-table, the signatures being placed between said guides with their respective folds resting upon the edge of the 60 toothed plate and over the knives d.

G represents the main needle-frame, and G' G' the frames upon which the needles for sewing the kettle-stitches are mounted.

g g' are rods upon which the kettle-stitch 65 frames G' slide within the main needle-frame G.

g' g'' represents the needles.

The needle-frames G G' are reciprocated for operation in connection with the signature by any suitable power mechanism, or such as is shown and described in the aforesaid application. 70

H represents an angular abutment-plate one being adjustably secured to the bottom of each of the kettle-stitch frames, at its outer fore corner, as shown in Fig. 11, its purpose being described hereinafter. 75

I represents an upright bent arm or hook attached to both the kettle-stitch frames in a position to overhang the needles g''. 80

J J' represent hinged bars attached at the fore end of the main needle-frame, and provided with semicircular notches j, through which the twines are passed to the needles. These hinged-bars, when swung outwardly, as 85 shown in dotted lines, Fig. 9, permit the adjustment of the needles while they are threaded when it is desired to sew narrower or wider signatures.

J' J' are adjustable lock-pins inserted 90 through holes in lugs on the main needle-frame and in the free ends of the hinged bars J.

K represents a transverse bar, suspended above the meeting point of the needle and feed-frames, more particularly speaking, at the 95 termination of the stroke of the feed-carriage.

K' represents presser-springs attached to the bar K by thumb screws k, which pass through slots in the bar to permit lateral adjustment of the springs for varying-sized signatures. 100 Presser-springs K' are each composed of two limbs, one limb, i, being provided with a pendent end, against which the fold of the signature on the advancing feed-carriage comes in contact to set the signature closely in position 105 upon the edge of the toothed plate of said feed-carriage, and the other limb, i', being bowed sufficiently to lie slightly below the plane or surface of the said toothed plate, so that its pressure while upon the signature and plate 110 will hold said signature firmly during the operation of the slitting-knives d and the sewing devices.

L represents a recessed plate or shelf mounted upon pillars L' at the rear end of the 115 main needle-frame.

l represents a transverse shaft, mounted in bearings l' upon plate L, and provided at its ends with pendent arms M, adjustably secured thereto.

M' represents coil-springs attached at one end to the pendent arms M, and at the other to arms m, projecting from the pillars L', as shown in Fig. 5. 120

N represents spring-bars projecting from collars N' on the shaft l, and provided with pendent inwardly-curved free ends n.

n' represents hook shape springs projecting from the collars N', beneath the spring-bars N.

O represents flat spring-plates, attached by thumb screws to plate L, adjacent the spring-bars N, and o are small eyes or perforations 130 in the spring-plates O.

5 O' represents eccentrics keyed to shaft *l* immediately above the free ends of the spring-plates O, so that they may be brought to bear upon the said plates by the contraction of the coil-springs M', as shown in Fig. 4.

10 P represents upright plates secured to the edge of plate L, in rear of the spring-bars N, and *p* are open slots or eyes in plate P through which the twines from the balls pass, and are guided to the springs N and *n*.

15 P' represents upturned plates adjustably secured to the rear upper face of the main frame A, in a position to trip the pendent arms M, and cause a slight backward rotation of shaft *l*, which raises the cams O' out of pressing engagement with the spring plates O.

20 Q represents the shuttle-race trough, which is arranged in duplicate at both sides of frame A, and Q' is the shuttle.

25 q q represent levers or arms pivoted to race-troughs Q, with their free ends projecting inwardly through openings in the sides of the frame A.

30 R represents horizontal bars, pivoted by a stud, *r*, to the race-troughs between levers *q* and the shuttle-race troughs. Stud *r* fits a hole or recess in the sides of said troughs, free to move inwardly or outwardly therein.

35 r' represents the short end of either bar R, and *r*'' the long end. Both ends *r*' and *r*'' are provided with studs or pins *s* *s*', which project through openings in the raceways a very slight distance beyond the inner walls thereof, but sufficient for the pin *s* to lock the shuttle firmly in place after its point has passed the pin *s*'.

40 The end *r*'' of bar R being of greater length than end *r*', the purchase on that end caused by the presence of the shuttle after its point has passed pin *s*' is greater and effectually holds the shuttle at the termination of its stroke, thereby preventing any rebounding thereof which would otherwise slacken the shuttle-thread, and lay it so as to be in inoperative relation with the kettle-stitch twines. This temporary locking device for the shuttle also serves to sustain it in position for receiving the full, effective blow of the picker-staff head R', as shown in Figs. 1 and 16.

45 S represents oblique offsets or shoulders at the inner ends of the shuttle-raceways, and S' are vertical pins or stops adjacent thereto on the race-troughs.

50 S'' represents notches in the forward edge of the feed-carriage, into which the pins S' rest at the end of the stroke of said carriage. When the feed-carriage has approached its limit of motion against stops S', the ends of the toothed plate cover the raceways, and the receptacles formed by the oblique offsets or shoulders S prevent the jamming or catching of the shuttle-thread between said toothed plate and the race-troughs on its way to the sewed signatures which are piled up in book form in rear 65 of the raceways.

T represents a transverse rod or bar suspended beneath the edge of the toothed plate

of the feed-carriage by a series of bumpers or presser-heads, T' T''.

70 In the passage of the shuttle across the machine its thread trails loosely in its wake, and in order that said thread may not accidentally drop into contact with the corners of the outer presser-heads, T', or any other obstruction, I provide said rod T, which catches 75 and supports it safely till it becomes taut in the fold of the signature.

75 The presser heads T' T'' rest against the hanging leaves of the signature during the sewing operation, and the outer ones, T', are supplied with bow springs *t*, which project upwardly from the tops of said bumpers directly beneath the slits in the ends of the unsewed signature on the feed-table, and serve as positive means for supporting the shuttle-thread and guiding it directly into the slits in the ends of the signatures to the kettle-stitch twines. The springs *t* project upwardly sufficient to guide the shuttle-thread directly in place into either of the open slits 90 at the end of each signature, and their tops being preferably on a line with the beveled edge of the teeth of the feed-table lie closely within the said slits. The object of the springs *t* is to provide guide-supports for the thread, 95 which supports will yield when the slitting-knives D d pass over them, and thereby obviate any collision to dull the knives, which would likely happen in case the tops of the bumpers were rigid.

100 Bumpers T' T'' are preferably secured to the bar U of the feed-table by means of thumb-screws whose heads rest in longitudinal T slots in the said bar U, for permitting the lateral adjustment of the bumpers for varying-sized signatures.

105 The operation of the tension and take-up devices is as follows: The twines pass from the feed-balls, which are held in a box or receptacle above the needle-frames, to the guide eye-plates P; thence beneath the bent free ends *n* of the springs N to the hook-springs *n*'; thence downwardly through the eyes *o* in spring-plates O; thence beneath the ends of springs O to the oscillating take-up frame V, 115 (shown in Fig. 1, and fully described in the aforesaid application.) From the take-up frame V, the middle twines pass through the eyes *j* in the forward end of the main needle-frame, and thence through the needles to a fastening-point beneath the needle-frames. The outer or kettle-stitch twines pass from the take-up frame V to the upright arms or hooks I, around which they are turned, and thence to the outer needles, *g*'' through them, and are secured as the other twines. In the advance movement of the needle-frames the twines are drawn out from their balls, and the proper tension exerted on them by means of the spring-plates O, which are depressed by cams O' on shaft *l*, and it in turn by pendent arms M and coil-springs M'. The pendent curved ends *n* of springs N press firmly upon the twines on the backward movement of the needle-frames.

when the pendent arms M strike the plates P', and the hook-springs n' are then depressed, which allows the passage of but sufficient twine to form the loops of the last sewed signature, and thereby draws the loops taut. As the kettle-stitch is made at but one end of the signature at each stroke of the needle-frames, only one of the kettle-stitch frames moves forward on the slides within the main 10 needle-frame. The other frame remains at rest in said needle-frame, and the twine which passes from the take-up frame V to the needle passes first around the upright hook I, which takes up the slack therein, as it does not combine with the shuttle thread, and maintains the proper tension on it to prevent its becoming loose or entangled. When the kettle-stitch is to be made at either end of the signature, the take up hook I does not act on the 15 twine or interfere with its operation in connection with the shuttle-thread.

The operation of either of the temporary locking devices for the shuttle is caused by the pendent angular plate H on either of the 20 advancing kettle-stitch frames coming in contact with the inner end of lever q.

Said plate H is slotted and adjustably attached to the bottom of said kettle-stitch frames by a screw passing through the slot, 25 so that it can be moved forward or backward on said frame to make allowance for any wear of the shuttle, and thereby secure the proper locking engagement through the instrumentality of said locking devices.

30 The operation of the knives for slitting the ends of the signature is as follows: The feed-carriage is moved toward the advancing needle-frame, and at the instant the points of the needles enter the fold of the signature the upper right arms d' of bars D strike against the transverse bar K, causing the knife-edges d to pass through the fold of the signature and cut a slit of sufficient length to accommodate the kettle-stitch threads. The knives are 35 then automatically retracted to their normal position by means of the presser-springs E.

I claim—

1. In a book-sewing machine, the combination, with the feed-table B'', of the signature-slitting knife-bars D d d', mounted thereon, and adapted to be operated at the termination of the stroke of said feed-table to slit the signature, and automatically retracted to their normal position, substantially as herein set forth.

2. In a book-sewing machine, the combination, with the feed-table B'' and knife-bar D, of an adjustable plate, D', upon which the said knife-bar is pivotally mounted and 60 adapted to operate in connection with varying-sized signatures, substantially as herein set forth.

3. In a book-sewing machine, the combination with the feed-table B'', knife-bars D, and 65 adjustable plates D', of the signature-guides F, adjustably secured upon said plates D' to adapt the machine to accommodate varying-

sized signatures, substantially as herein set forth.

4. In a book-sewing machine, the combination, with the feed-table B'', having tenoned edges b, fitting in grooves in the main frame and provided with notches b', of vertical rods C, thrust upwardly into locking engagement with said feed-table by a cam, e, on the driving-shaft c', and disengaged, substantially in the manner and for the purpose specified.

5. In a book-sewing machine, the combination, with the feed-table B'', of a transverse rod, T, suspended beneath the forward signature-fold edge of the table and adapted to support the shuttle-thread during the passage of the shuttle across the machine to insure its proper connection with the needle-twines and obviate any entanglement thereof, substantially as 85 herein set forth.

6. In a book sewing machine, the combination, with the feed-table B'', of the presser-heads or bumpers T' T'', attached beneath the edge of the toothed plate of the table, the end or outer bumpers, T', being provided with overhanging springs t to guide the shuttle-thread into the slits in the ends of the signatures, 90 substantially as herein set forth.

7. In a book-sewing machine, the combination, with the shuttle-raceways Q, of the compression or lock pins s s', mounted upon the pivotal bar R, the pressure-lever q, and plate H, carried by the reciprocating needle-frame adapted to catch and hold the shuttle at either 100 end of its stroke, substantially as herein set forth.

8. In a book-sewing machine, the combination, with the feed-table B'' and carriage B, of the shuttle raceways or troughs Q, provided 105 at their inner ends with an oblique offset or shoulder, S, and a pin, S', the offset being adapted to form a receptacle for the shuttle-thread, to prevent its jamming between the feed-table and raceway when stretched between the shuttle and the sewed signatures, and the pin to serve as a positive stop for the feed-carriage, substantially as herein set forth.

9. In a book-sewing machine, the combination, with the feed-table, of a transverse bar, 115 K, rigidly mounted upon the main frame and provided with adjustable springs K' i i', which closely set the fold of the signature upon the toothed edge of said feed table and press it down firmly during the slitting and sewing 120 operation, substantially as herein set forth.

10. In a book-sewing machine, the combination, with the main needle-frame G, of hinged bars J, provided with open thread-passages j, and attached to the fore end of said needle-frame, being locked in position and adapted to be opened for the adjustment of the needles while threaded, substantially as herein set forth.

11. In a book-sewing machine, the combination, with the kettle-stitch frames G' G', of 130 upright arms or hooks I, adapted to receive a turn or turns of the kettle-stitch twines, and form a take-up for the twine which is not to

be looped with the shuttle-thread, substantially as herein set forth.

12. In a book-sewing machine, the combination, with the reciprocating needle-frames $G G'$, of tension spring-bars N , take-up hooks n' , plates O , and eccentrics O' , mounted upon a shaft provided with pendent arms M , and operated for the forward movement of the needle-frames by coil-springs M' , and for the back-

ward movement thereof by a stop, P' , substantially as herein set forth.

In testimony of which invention I hereunto set my hand in the presence of two subscribing witnesses.

EDWARD CHESHIRE.

Witnesses:
